COIN AND KEY HOLDER
Donald J. Hankey, 7835 E. Loma Land Drive,
Scottsdale, Ariz.
Filed Mar. 10, 1965, Ser. No. 438,596
7 Claims. (Cl. 133—6)

This invention relates to a coin and key holder and more particularly to a coin and key holder particularly adapted for use by motorists for retaining keys and also for efficiently retaining coins readily available for use in parking meters.

Various prior art coin and key holders have been relatively complicated, yet also bulky, difficult of operation and of structural arrangements which are not durable or reliable.

Accordingly, it is an object of the present invention to provide a very simple, efficient and economical coin and key holder composed of only two parts, which are very substantial, durable, reliable of operation, simple to use and also compact.

Another object of the present invention is to provide a coin and key holder which may be composed of a generally cylindrical body of plastic or other material, having a cylindrical cavity therein and a resilient wire loop having detent portions engageable with the body and having key retaining portions overlying the cavity and whereby resilient release of the detent portions of the wire loop permits the key retaining portions to be removed from interfering relation with coins in the cavity so that the coins may readily be removed therefrom when needed.

Another object of the invention is to provide a novel coin and key holder having a resilient wire loop structure so designed that it readily and safely retains keys when removed from the coin retaining body of the invention.

Another object of the invention is to provide a coin and key holder in which a key retaining loop readily maintains a plurality of coins in a stacked compact position in a generally cylindrical body member, thereby providing for the retention of a substantial number of keys and a substantial number of different sized coins in a very compact structure.

Another object of the invention is to provide a novel coin and key holder employing a novel body and key retaining loop structure wherein portions of the resilient key retaining loop overlie coins and hold them captive in a cavity in the body member and whereby detent portions formed on the loop engage detent portions of the body to hold the key retaining portions over an open side of the cavity in the body member to hold coins therein.

Further objects and advantages of the invention may be apparent from the following specification, appended claims, and accompanying drawings, in which:

FIG. 1 is a side elevational view of a coin and key holder, in accordance with the present invention, showing a portion of a key retaining loop thereof broken away and in section to amplify the illustration;

FIG. 2 is an elevational view thereof taken from the line 2—2 of FIG. 1;

FIG. 3 is an enlarged fragmentary sectional view taken from the line 3—3 of FIG. 1, showing a portion of the wire loop member of the invention in elevation;

FIG. 4 is an enlarged view of a modified form of the invention showing portions thereof broken away and in section and illustrating a varying position of the key retaining loop member by broken lines;

FIG. 5 is a fragmentary sectional view taken from the line 5—5 of FIG. 4;

FIG. 6 is an enlarged fragmentary sectional view taken from the line 6—6 of FIG. 4; and

2

FIG. 7 is a fragmentary sectional view taken from the line 7—7 of FIG. 5.

As shown in FIGS. 1 and 2 of the drawings, the coin and key holder of the present invention is provided with a body member 10 which may be made of plastic, metal or other material. This body member 10 is provided with a cavity 12 which is generally circular and provided with a closed side 14 and an open side 16. The body member 10 is generally circular in outline, but may be of different shape and also the cavity, may if desired, be of a different shape but provided only with a closed side and an open side.

The body 10 is provided with an external groove portion 18 in which opposed recess portions 20 are located. These recess portions 20 extend from an inner wall 22 of the cavity 12 to an outer portion of the body 10 communicating with the groove portion 18. A wire key retaining loop 24 is provided with opposed detent portions 26 and 28, which are resiliently urged toward each other by the resilient character of the wire loop 24. The detent portions engaged in the openings 20 are inwardly directed convex portions of the resilient wire and as shown in FIG. 3 the convex curvature of these detent portions is directed inwardly to overlie the peripheries 30 of coins in the cavity 12. The resilient loop 24 is also provided with abutment portions 32 which bear against the outer side of the body 10 in the groove 18 to stabilize the disposition of the loop portion 24 for holding keys thereon. The keys may be threaded over either one of the opposite ends 34 or 36 of the resilient wire loop and may be disposed upon an intermediate loop portion 38, all as shown best in FIGS. 1 and 2 of the drawings.

A modification of the invention shown in FIGS. 4, 5, 6 and 7 is considered to be the preferred form of the invention. This modification of the invention comprises a body 40 which may be circular or some other shape, and this body 40 is provided with a cavity 42 therein which may have a circular wall and may be provided with a closed side 44 and an open side 46. Although the disclosure relates to a cavity 42 having a curved wall, this wall may be rectangular or any other wall shape desired, in order to hold coins at their peripheries 30 in the body 40.

This body 40 is provided with a slot 48 in its side wall having opposed recess portions 50 and 52, which engage and hold portions 54 and 56 of a wire loop member 58. This loop member 58 is provided with joggled portions 60 disposed normally inward relative to the recess portions 50 and 52 in the slotted portion 48, all as shown best in FIGS. 5 and 6 of the drawings.

The joggled portions disposed inwardly of the recess portions lie in further recess portions 62 and 64 forming abutments tending to resist radial displacement of the joggled portions 60 relative to the center of the cavity 42.

The joggled portions 60 are integral with key retaining portions 66 and 68 which extend across the cavity 42, as shown best in FIGS. 4 and 5, and these portions 66 and 68 are integral with respective ends 70 and 72 forming opposite ends of the loop member 58 and these ends are held in a recess 74 in the side wall of the body 40.

It will be seen that the coin retaining portions 66 and 68 are spaced a considerable distance from the enclosed side 44 of the cavity 42, so that several coins may be retained in the cavity 42 by the coin retaining portions 66 and 68 and that any coins disposed therein and as illustrated by broken lines A in FIG. 4 of the drawings, may not be removable or displaced from the cavity 42 merely by accident, as for example, the cavity 42 is large enough for conventional coins such as nickels and dimes may also be held in the cavity without danger of loss, due to the fact that dimes may assume a diameter and

position as indicated by broken lines A in FIG. 4 of the drawings, and yet be retained by the coin retaining members 66 and 68. At the same time nickels may be held in the cavity and they may be of such diameter as to fit quite closely within the confines of the cavity 42.

It will be seen that a key or keys 76 may be positioned on the wire loop 58 and that the coin retaining portions 66 and 68 are disposed in a converging relation from the loop 58 and are converged inwardly toward the body 40 when in a removed broken line position B shown in FIG. 4 of the drawings. When the converging coin retaining elements 66 and 68 are in the broken line position B, it will be seen that resilient character of the loop 58 tends to hold these portions apart as well as the detent portions 60, so that normal resilient tendency of the loop 58 is to hold the detent portions 60 apart and in engagement with the ledges 62 and 64 and within the recesses 50 and 52 in order that the body be efficiently and rigidly retained on the loop 58.

When it is desired to remove the loop 58 from the body 40, the loop may be squeezed together, thereby forcing the detent portions 60 closer together and releasing them from the ledges 62 and 64.

When it is desired to replace the loop 58, it may be forced in a direction of an arrow C in FIG. 4 of the drawings, whereby the converging coin retaining portions 66 and 68 pass into the slotted portion 48 and engage the recesses 50 and 52 and are, thus, cammed closer together until the detent portions 60 snap into position in engagement with the ledge portions 62 and 64, hereinbefore described.

The detail of the recess portions 62 and 64 is illustrated in FIG. 7, showing the structure in section and illustrating one detent portion 60 firmly engaged with a ledge 64 and showing the respective integral portion of the loop portion engaged in the recess 52 at one side of the slotted portion 48.

It will be obvious to those skilled in the art that operation simplicity and economy of the coin and key holder, in accordance with the present invention, is advantageous and that several keys may be retained on the loop 58 and may be removed without having the keys readily accidentally displaced from the loop, while coins are being removed from the cavity 42. This is due to the fact that the coin retaining portions 66 and 68 are disposed in converging relationship and that their opposite ends do not readily permit keys to reach the space between them, due in part to the joggled portion 60 and to the slight spaced relationship of the ends 70 and 72 when the loop member is removed from the body 40.

It will be obvious to those skilled in the art that various modifications of the present invention may be resorted to in a manner limited only by a just interpretation of the following claims.

I claim:

1. In a coin and key holder the combination of: a body member having a coin holding cavity therein; and a resilient wire loop member removably engaged with said body; and coin retaining portions of said wire loop member overlying said cavity to retain coins therein said cavity having a closed side and an open side, said cavity adapted to hold a stack of coins in flat side-to-side contact with each other, said cavity having a central axis directed normally through coins at right angles to the sides of said coins, said open side of said cavity disposed to receive coins in a direction normal to their sides, said coin retaining portions of said resilient wire loop member disposed to be parallel to the sides of coins in said cavity and to retain coins against removal from said cavity in a direction parallel to said axis and normal to the sides of said coins said retaining portions completely removable from overlying and obstructing position throughout the entire cross-sectional area of said cavity alternately to dispense coins therefrom.

2. In a coin and key holder the combination of: a body

5 member having a coin holding cavity therein; and a resilient wire loop member removably engaged with said body; and coin retaining portions of said wire loop member overlying said cavity to retain coins therein said cavity having a closed side and an open side, said cavity adapted to hold a stack of coins in flat side-to-side contact with each other, said cavity having a central axis directed normally through coins at right angles to the sides of said coins, said open side of said cavity disposed to receive coins in a direction normal to their sides, said coin retaining portions of said resilient wire loop member disposed to be parallel to the sides of coins in said cavity and to retain coins against removal from said cavity in a direction parallel to said axis and normal to the sides of said coins said retaining portions completely removable from overlying and obstructing position throughout the entire cross-sectional area of said cavity alternately to dispense coins therefrom; opposed recess portions in said body adjacent said cavity; opposed detent portions of said loop member in said opposed recess portions; the resilient character of said loop member tending to hold said detent portions in engagement with said opposed recess portions.

3. In a coin and key holder the combination of: a body member having a coin holding cavity therein; and a resilient wire loop member removably engaged with said body; and coin retaining portions of said wire loop member overlying said cavity to retain coins therein said cavity having a closed side and an open side, said cavity adapted to hold a stack of coins in flat side-to-side contact with each other, said cavity having a central axis directed normally through coins at right angles to the sides of said coins, said open side of said cavity disposed to receive coins in a direction normal to their sides, said coin retaining portions of said resilient wire loop member disposed to be parallel to the sides of coins in said cavity and to retain coins against removal from said cavity in a direction parallel to said axis and normal to the sides of said coins said retaining portions completely removable from overlying and obstructing position throughout the entire cross-sectional area of said cavity alternately to dispense coins therefrom; opposed recess portions in said body adjacent said cavity; opposed detent portions of said loop member in said opposed recess portions; the resilient character of said loop member tending to hold said detent portions in engagement with said opposed recess portions.

4. In a coin and key holder the combination of: a body member having a coin holding cavity therein; and a resilient wire loop member removably engaged with said body; and coin retaining portions of said wire loop member overlying said cavity to retain coins therein said cavity having a closed side and an open side, said cavity adapted to hold a stack of coins in flat side-to-side contact with each other, said cavity having a central axis directed normally through coins at right angles to the sides of said coins, said open side of said cavity disposed to receive coins in a direction normal to their sides, said coin retaining portions of said resilient wire loop member disposed to be parallel to the sides of coins in said cavity and to retain coins against removal from said cavity in a direction parallel to said axis and normal to the sides of said coins said retaining portions completely removable from overlying and obstructing position throughout the entire cross-sectional area of said cavity alternately to dispense coins therefrom; opposed recess portions in said body adjacent said cavity; opposed detent portions of said loop member in said opposed recess portions; the resilient character of said loop member tending to hold said detent portions in engagement with said opposed recess portions; a slotted portions in

said body member directed generally radially with respect to said cavity and extending from said cavity to an outer surface of said body member; said recess portions disposed in opposite sides of said slotted portion; said detent portions comprising joggled portions of said loop member, said joggled portions engaged in said recess portions; and ledge portions of said body member adjacent said recess portions tending to retain said joggled portions in juxtaposition in said body member.

5. In a coin and key holder the combination of: a body member having a coin holding cavity therein; and a resilient wire loop member removably engaged with said body; and coin retaining portions of said wire loop member overlying said cavity to retain coins therein said cavity having a closed side and an open side, said cavity adapted to hold a stack of coins in flat side-to-side contact with each other, said cavity having a central axis directed normally through coins at right angles to the sides of said coins, said open side of said cavity disposed to receive coins in a direction normal to their sides, said coin retaining portions of said resilient wire loop member disposed to be parallel to the sides of coins in said cavity and to retain coins against removal from said cavity in a direction parallel to said axis and normal to the sides of said coins said retaining portions completely removable from overlying and obstructing position throughout the entire cross-sectional area of said cavity alternately to dispense coins therefrom; opposed recess portions in said body adjacent said cavity; opposed detent portions of said loop member in said opposed recess portions; the resilient character of said loop member tending to hold said detent portions in engagement with said opposed recess portions; a slotted portion in said body member directed generally radially with respect to said cavity and extending from said cavity to an outer surface of said body member; said recess portions disposed in opposite sides of said slotted portion; said detent portions comprising joggled portions of said loop member, said joggled portions engaged in said recess portions; and ledge portions of said body member adjacent said recess portions tending to retain said joggled portions in juxtaposition in said body member; said coin retaining portions integral with said joggled portions and extending beyond said joggled portions and over said cavity, to an opposite side thereof from said slotted portion; and opposite ends of said loop member integral with said coin retaining portions; and a second recess means in said body member in which said opposite ends are retained.

6. In a coin and key holder the combination of: a body member having a coin holding cavity therein; and a resilient wire loop member removably engaged with said body; and coin retaining portions of said wire loop member overlying said cavity to retain coins therein said cavity having a closed side and an open side, said cavity adapted to hold a stack of coins in flat side-to-side contact with each other, said cavity having a central axis directed normally through coins at right angles to the sides of said coins, said open side of said cavity disposed to receive coins in a direction normal to their sides, said coin retaining portions of said resilient wire loop member disposed to be parallel to the sides of coins in said cavity and to retain coins against removal from said cavity in a direction parallel to said axis and normal to the sides of said coins said retaining portions com-

pletely removable from overlying and obstructing position throughout the entire cross-sectional area of said cavity alternately to dispense coins therefrom; opposed recess portions in said body adjacent said cavity; opposed detent portions of said loop member in said opposed recess portions; the resilient character of said loop member tending to hold said detent portions in engagement with said opposed recess portions; a slotted portion in said body member directed generally radially with respect to said cavity and extending from said cavity to an outer surface of said body member; said recess portions disposed in opposite sides of said slotted portion; said detent portions comprising joggled portions of said loop member, said joggled portions engaged in said recess portions; and ledge portions of said body member adjacent said recess portions tending to retain said joggled portions in juxtaposition in said body member; said coin retaining portions integral with said joggled portions and extending beyond said joggled portions and over said cavity, to an opposite side thereof from said slotted portion; and opposite ends of said loop member integral with said coin retaining portions; and a second recess means in said body member in which said opposite ends are retained.

7. In a coin and key holder the combination of: a body member having a coin holding cavity therein; and a resilient wire loop member removably engaged with said body; and coin retaining portions of said wire loop member overlying said cavity to retain coins therein said cavity having a closed side and an open side, said cavity adapted to hold a stack of coins in flat side-to-side contact with each other, said cavity having a central axis directed normally through coins at right angles to the sides of said coins, said open side of said cavity disposed to receive coins in a direction normal to their sides, said coin retaining portions of said resilient wire loop member disposed to be parallel to the sides of coins in said cavity and to retain coins against removal from said cavity in a direction parallel to said axis and normal to the sides of said coins said retaining portions completely removable from overlying and obstructing position throughout the entire cross-sectional area of said cavity alternately to dispense coins therefrom; said cavity substantially cup-shaped and provided with a generally circular wall portion and one closed side; said cavity having an open side, said coin retaining portions overlying said open side of said cavity.
